UNITED STATES PATENT OFFICE

150,197

DESIGN FOR A BURIAL CASKET

John M. Beach, Grand Rapids, Mich.

Application April 10, 1946, Serial No. 128,461

Term of patent 3½ years

(Cl. D19—1)

To all whom it may concern:

Be it known that I, John M. Beach, a citizen of the United States, residing at Grand Rapids, in the county of Kent and State of Michigan, have invented a new, original, and ornamental Design for Burial Caskets, of which the following is a specification, reference being had to the accompanying drawing, forming part thereof:

Fig. 1 is a side elevational view of a burial casket, showing my new design.

Fig. 2 is a top plan view; and

Fig. 3 is an end elevational view thereof.

I claim:

The ornamental design for a burial casket as shown.

JOHN M. BEACH.
